UNITED STATES PATENT OFFICE.

SAMUEL B. STEWART, OF NEW ORLEANS, LOUISIANA.

FILTER.

No. 821,442.

Specification of Letters Patent.

Patented May 22, 1906.

Application filed February 14, 1905. Serial No. 245,596.

To all whom it may concern:

Be it known that I, SAMUEL B. STEWART, a citizen of the United States, residing at New Orleans, in the parish of Orleans and State of 5 Louisiana, have invented certain new and useful Improvements in Filters, of which the following is a specification.

My invention relates to improvements in filters; and the object of my invention is the 10 provision of a filter adapted to be attached to the usual spigot or supply-pipe under the pressure of the main of the waterworks and which will have a large capacity for filtering the water and which will have means for cleaning any of its parts, the mechanism embodying the simplest, cheapest, and most practical construction.

To attain the desired object, my invention 15 consists of a filter embodying novel features of construction and combination of parts substantially as disclosed herein.

Figure 1 represents a sectional view of my filter. Fig. 2 represents a top plan view of 20 the cleaning device, and Fig. 3 represents an enlarged side elevation of the cleaning device detached.

In the drawings the letter H represents the shell or casing of my filter, which is supported upon a base H', and this casing is provided with the central discharge-opening J' for discharging the filtered material to the pipe N and with the inlet J, and upon the central pipe J² is mounted the filtering-stone S, to 25 the upper end of which pipe is connected or formed the stem M' to receive the handle M. The casing is also provided with a flushing outlet-pipe O and with a small cock or faucet K. Mounted on the stem M' and above the 30 ends of the filtering-stone are the cross-heads A and B, to which are connected the side vertical strips G, and to one of said strips is secured the curved plates E, the inner or free ends of which are connected to the scraping- 35 plate or cleaner C, which scraper is held normally in contact with the filtering-stone by 40 means of the spring F, connected to each end of the scraper and always exerting their ten-

sion to hold the scraper in contact with the face of the filter-stone.

In operation the water enters the casing, passes through the filter-stone, and is discharged at the lower portion J' through pipe N, and when desired to clean the filter-stone it is simply necessary to turn the crank which 50 revolves the scraper against the surface of the stone and entirely removes all sediment or slime from the stone, and the water flushes and carries off such sediment or slime, as will be understood. It is evident that I provide 55 a filter which will perform the function of filtering in a thorough manner and which can be quickly cleaned without in any manner affecting the interior mechanism.

I claim—

In a filter, the combination with a casing, an inlet and an outlet near the top of said casing, said inlet and outlet provided with valves or cocks, a base portion upon which the casing rests having a central depending ring forming 70 a chamber, a cap or covering for said chamber, a water-discharge pipe leading from said chamber, a flushing-outlet on one side of the base, a central discharge-pipe registering with said discharge-chamber, a stone rigidly mounted 75 on said pipe, a stem rotatably mounted centrally in the top of the casing, a handle on said stem, a frame mounted on said stem and consisting of an upper and lower head or cross-piece having angular ends, flat vertical 80 connecting-bars secured to said angular ends, a series of flat segmental curved spring-arms having one end secured to the said vertical connecting-bars, an angle-bar connected to the free ends of said curved spring-arms, a 85 vertical scraper-bar connected to one face of the angle-bar, and a pair of coiled springs each having one end connected to the scraper-bar and their other ends connected to the upper and lower heads of the frame.

In testimony whereof I affix my signature in presence of two witnesses.

SAMUEL B. STEWART.
